UNITED STATES PATENT OFFICE.

OTTO BARK, OF CHICAGO, ILLINOIS, ASSIGNOR, BY DIRECT AND MESNE ASSIGNMENTS,
TO LEAKPROOF RADIATOR CO., OF CHICAGO, ILLINOIS, A CORPORATION.

RADIATOR-TUBING.

1,377,385.

Specification of Letters Patent. Patented May 10, 1921.

Application filed October 8, 1919. Serial No. 329,394.

To all whom it may concern:

Be it known that I, OTTO BARK, a citizen of the United States of America, and a resident of Chicago, county of Cook, and State 5 of Illinois, have invented certain new and useful Improvements in Radiator-Tubings, of which the following is a specification.

The main objects of this invention are to provide an improved construction for reinforcing metal tubing made from thin flexible sheet metal which except for some reinforcing means would be practically incapable of maintaining its shape; to provide an improved combination of a reinforcing 10 means with the sheet metal from which the tubing is made so as to efficiently stiffen and strengthen the tube; to provide an improved arrangement of this kind for flat metal tubing for use particularly as radiator construction to be used as a part of the 15 circulating system for gas engines; and to provide for a further strengthening and stiffening of said tube by transversely corrugating the same.

20 A specific embodiment of this invention is shown in the accompanying drawings, in which—

Figure 1 is a plan of a section of a piece of tubing constructed in accordance with 25 this invention.

Fig. 2 is a side view thereof.

Fig. 3 is an enlarged cross-sectional view taken on the line 3—3 of Fig. 2.

Fig. 4 is a similar cross-sectional view of 30 a modified form of tubing.

A reduction of this invention to actual practice involves the use of a number of comparatively stiff wires intimately secured in the edges of tubing made up of comparatively thin flexible sheet metal which except 40 for some stiffening and strengthening means would be incapable of sufficiently maintaining its shape to permit very extensive use. The invention is particularly applicable for

45 use in making flat metal tubing to be used for the construction of radiators intended for use as a part of the circulating system for gas engines. In such constructions it is important to have the material from which 50 the tubing is made of as thin construction as possible in order to facilitate the radiation of heat.

In the specific embodiment herein shown, the tubing is made up either of a single 55 sheet of metal 1 doubled upon itself and se-

cured together by a seam 2, as shown in Fig. 3, or two pieces of metal 3 and 4 secured together along their edges by seams 5 as indicated in Fig. 4. The construction herein illustrated being particularly designed for use in radiator construction, is 60 illustrated in the form of a flat narrow tubing of elongated cross-section.

The reinforcing means by which the tubing is stiffened and strengthened comprises 65 wires 6 intimately secured in the edges 7 and 8 of the tube by having the metal partially embrace said wires. These wires are preferably of larger diameter than the normal distance between the sides of the tube, 70 so that the metal may be formed around the wire to embrace more than half of the periphery. This will insure the wires being retained in proper position.

Where the tubing is of the form shown 75 in Fig. 4, the wires 6 may be of smaller diameter than in the modification shown in Fig. 3, for the reason that the seams 5, being at the edges of the tube, constitute a partial reinforcement for the tubing.

In order to make the tubing particularly useful for radiator constructions and incidentally to further strengthen the same, the tubing is preferably transversely crimped or corrugated as clearly shown in the drawings. After the tubing has been completely formed, the seam or seams are soldered so as to make the tubing water-tight. With the modification shown in Fig. 4, this is most easily accomplished by dipping the 90 tube edgewise into solder and holding it long enough to allow the solder to permeate through the seam layers and around the wires. This tends to further strengthen the edges and also permits repairs to be readily 95 made, for if any leak occurs at one of the edges, the application of heat at such point will melt the adjacent solder and cause it to fill the opening.

The tubing is preferably made up in stock 100 lengths, after which it can be cut up into suitable lengths for the formation of radiator structures in some suitable and well-known manner. The finished structure will provide an abundance of radiating surface 105 and efficient cooling of the circulating medium will result.

As will be obvious, other modifications may be made and those shown may be further modified or altered or have details 110

thereof omitted without departing from the spirit of this invention as defined by the following claims.

I claim:

5. 1. An article of manufacture of the class described comprising a tube of narrow oblong cross section made up of thin flexible sheet-metal, the edges of which are joined by the usual interlocking seam, and stiffening wires embedded in said tube along the lateral edges thereof.
10. 2. An article of manufacture of the class described, comprising a tube of narrow oblong cross-section made up of two sheets 15 of thin flexible sheet metal having the edges of one sheet joined to the corresponding edges of the other sheet by the usual interlocking seam disposed along the lateral edges of said tube, and stiffening wires secured along said lateral edges by having the metal of said tube partially embracing said wires.
20. 3. An article of the class described, comprising a flat tube formed of sheet metal,

and stiffening wires extending along the 25 edges thereof for reinforcing the same, said wires being secured in place by having the metal of said tube partially embrace said wires, said tubing being transversely corrugated.

30. 4. A reinforced flat metal tube, comprising two opposed and spaced-apart strips of sheet metal seamed together at their edges, and wires extending along the tube adjacent to said seams and secured in place by 35 bends in the tube, said seams and wires serving to stiffen and strengthen said tube.

5. A reinforced flat metal tube, comprising two opposed and spaced-apart strips of sheet metal seamed together at their edges, 40 and wires extending along the tube adjacent to said seams and secured in place by bends in the tube, said seams and wires serving to stiffen and strengthen said tube, said tube being transversely corrugated.

Signed at Chicago this 4th day of October, 1919.

OTTO BARK.
